UNITED STATES PATENT OFFICE.

JOSEPH EDMUND BLAKE, OF GARDNER, MASSACHUSETTS.

DESIGN FOR A TOY SHACKLE.

61,149.

Specification for Design.

Patented July 4, 1922.

Application filed January 9, 1922. Serial No. 123. Term of patent 3½ years.

To all whom it may concern:

Be it known that I, JOSEPH E. BLAKE, a citizen of the United States of America, residing at Gardner, in the county of Worcester and State of Massachusetts, have invented a new, original, and ornamental Design for a Toy Shackle, of which the following is a specification, reference being had to the accompanying drawings, forming a part hereof.

The figure is a perspective view showing my new design of toy shackle.

I claim:

The ornamental design for a toy shackle as shown.

JOSEPH EDMUND BLAKE.
